PRESSURIZED CUPOLAS

Herbert A. Reece, Cleveland Heights, Ohio

Application April 21, 1951, Serial No. 222,190

11 Claims. (Cl. 266—25)

1

This invention relates, as indicated, to pressurized cupolas.

It has heretofore been proposed to solve the problem of uniform distribution of air through a cupola charge, as by the use of a removable orifice ring, which creates the desired static pressure in the stack, the velocity of air through the charge remaining constant since it is governed by the orifice ring and the volume of air it handles. Such a pressurized cupola is described on page 127 of the September 1950 issue of *The Foundry*.

The pressurizing of cupolas in this manner has been extremely difficult of attainment, due to the fact that the circular shape or design of the conventional type of cupola has necessitated, for this purpose, either the use of complicated and expensive equipment of the iris diaphragm type, or the use of cup and cone or bell and hopper equipment, borrowed largely from blast furnace design or practice.

I have found that the problem of pressurizing a cupola can be solved in a relatively simple and inexpensive manner by utilizing a cupola of rectangular cross-section, as disclosed, for example, in my Patent No. 2,471,776.

A cupola of this rectangular shape lends itself readily to the incorporation therein of pressurizing means or devices, which are of extremely simple construction and which can be installed at a fraction of the cost of installing pressurizing equipment in cupolas of circular or conventional design.

By utilization of pressuring means or devices in accordance with my invention, I am able to use relatively high air pressures in the combustion zone of the cupola, thereby providing improved combustion, hotter iron, increased melt per square inch of cupola cross-sectional area, greater fuel economy and more uniform operation of the cupola, and to avoid or minimize bridging of the cupola by slag.

Other objects and advantages of the invention will become apparent during the course of the following description, when read in conjunction with the drawings forming a part of this specification, and in which like numerals are employed throughout to designate like or corresponding parts.

In said annexed drawings,

Fig. 1 is a fragmentary vertical cross-sectional view through a cupola similar to that shown in my aforesaid Patent No. 2,471,776, and having incorporated therein one form of pressurizing means embodying novel features of the invention;

2

Fig. 2 is a fragmentary vertical cross-sectional view, taken on the line 2—2 of Fig. 1;

Fig. 3 is a fragmentary transverse or horizontal cross-sectional view, taken on line 3—3 of Fig. 1, with two of the three plates in lowered position;

Fig. 4 is a view similar to Fig. 3, but showing a modified form of pressurizing means or device;

Fig. 5 is a fragmentary vertical cross-sectional view taken on the line 5—5 of Fig. 4;

Fig. 6 is a fragmentary view, showing in greater detail the plate lock mechanism of Fig. 4, and

Fig. 7 is a fragmentary cross-sectional view, taken on the line 7—7 of Fig. 6.

Referring more particularly to Figs. 1, 2 and 3 of the drawings, the cupola will be seen to comprise an upright hollow cupola body having opposed substantially flat side walls 1 and 2 and opposed substantially flat end walls 3 and 4. The side and end walls are formed of an outer metallic shell 5 and a refractory lining 6.

The wall 2 has a charging opening therein, defined by upper and lower edges 7 and 8 respectively, and side edges 9 and 10.

Directly opposite the aforesaid charging opening, the back wall 1 of the cupola is constructed to provide a recess 11, which is defined by a horizontal rearwardly extending ledge 12, sides 13 and 14 which are rearward extensions of the end walls 3 and 4 respectively, a rearwardly and downwardly inclined top wall 15 and a rear wall or back 16, which inclines rearwardly from the rear edge of the ledge 12 to the rear edge of the top wall 15.

Disposed within the recess of area thus described is a series of plates 17, 18 and 19, which are pivotally secured at their lower edges to a pivot pin or shaft 20, the ends of which are secured in the walls 13 and 14.

The plates 17, 18 and 19 are of substantially rectangular form and are preferably made of stainless steel or other metal resistant to corrosion and heat. The plate 17 has a rectangular opening 17a therein of fairly large area. The plate 18 has a rectangular opening 18a therein of somewhat less area than the area 17a, and the plate 19 has a rectangular opening 19a therein, of somewhat less area than the area 18a. The openings 17a, 18a and 19a are aligned axially with each other and with the axis or center of the shaft, when in operative position.

The openings in the plates may be of various areas or sizes, and the areas can be predetermined in accordance with actual operation conditions of the cupola. In a cupola, for example, having a stack or shaft whose cross-section is 36" x 48", or

3

a cross-sectional area of 1728 square inches, a plate or leaf having a rectangular cut out or opening 23" x 30", or cross-sectional area of 690 square inches, decreases or constricts the shaft opening 40%.

I have found, however, that a most desirable arrangement is provided by utilizing three plates or leaves, in which the plate 17 provides a constriction of 80%, the plate 18 a constriction of 60% and the plate 19 a constriction of 40%. Such an arrangement has been found highly effective in maintaining high melting zone pressures.

Cupolas ordinarily operate at an average pressure of about 1 pound per square inch, but by means of this method of constructing the shaft area, operating pressures can be increased to 2, 3 and 4 or more pounds per square inch.

When not in use, the plates 17, 18 and 19 are stored in the recess 11 of the cupola, with their upper edges resting against the inclined back wall 16, in which open position, the plates are inclined and cannot be dislodged unless pulled forwardly, as by means of a hooked rod inserted through the opening 10 and into an opening 21 adjacent the upper edge of each plate. In order to insure, against accidental dislodgment of the plates 17, 18 and 19, as under certain operating conditions of the cupola, in which a strong suction may be created in the recess 11, a latch member 13a (Figs. 1 and 2) is provided, which extends through the side wall 13 and may be slid to the plate-latching position shown in solid lines in Fig. 2, or to the position indicated by the broken lines in Fig. 2, in which latter position, the plates may be pulled forwardly.

As each plate is pulled forwardly, it falls by gravity to the operative, closed, or horizontal position shown in broken lines in Fig. 1, in which position, the plates are supported by brackets or stops 22 extending inwardly from the walls of the cupola. When all of the plates are in operative position, only the plate 19 is effective to constrict the cupola area, since the opening in this plate is smaller than the openings in the other plates. When only the plates 17 and 18 are in horizontal position, only the plate 18 is effective to constrict the cupola area, since the opening in this plate is smaller than the opening in plate 17.

The cupola may be charged either before any of the plates have been moved into operative position, or may be charged by dumping or raking the raw materials through the openings in the plates while the plates are in operative position. To facilitate such charging through the openings, the openings may, if desired, be provided with inclined downwardly extending sides forming hoppers, it being understood, however, that this latter expedient serves to further constrict the openings, which additional restriction must be compensated for by making the openings larger.

When using mechanical charging devices, motor-driven blades can be used to push the raw materials to the leaf or blade hoppers.

It is thus seen that I have provided a means of effectively providing for uniform distribution of air through a cupola charge, that is to say, for the pressurizing of cupolas and that the means which I have provided for this purpose is of extremely simple construction and relatively inexpensive to install.

Although the aforesaid pressurizing means has been designed particularly for use or incorporation in a cupola of rectangular design, as shown in my aforesaid patent, it is to be understood

4

that the principle of the invention can also be incorporated, by suitable modification thereof, in cupolas of circular or conventional design.

In Figs. 4, 5, 6 and 7 of the drawings, there is illustrated a modification of the invention, in which the back wall of the cupola is not modified, as in the previously described construction, but instead, a plate 23 is provided of substantially the same exterior dimensions as the shaft of the rectangular cupola.

The plate 23 is provided with spaced pairs of openings 24 and 25, each pair of openings being adapted to be completely closed by means of rectangular closure plates 26 which are connected to each other as by a connecting arm 27. The arm 27 is guided for slidable reciprocal movement in a guide member 28, which is secured to the plate 23. To further insure rectilinear movement of plates 26, guides 29 are secured to the plate 23, these guides having portions 30 which abut the sides edges of the plates 24.

The plates 26 are movable from the solid line position shown in Fig. 4, in which position the openings 24 and 25 are completely closed, to the broken line position shown in this figure, in which the openings 24 and 25 are completely open.

By movement of one or both pairs of the plates 26 to selected positions between the aforesaid completely closed or completely open position, an almost infinite variation in the area or size of the air passageways through the plate 23 may be attained, for pressurizing purposes.

The plate 23 is also provided at one edge with a flange or lip 31, of arcuate cross-section, the function of which will hereinafter appear.

The plate 23 is rigidly supported upon a shaft 32 which extends through the end walls of the cupola. This shaft may be rotated, as by a reversing motor 33 to quickly rotate the plate 23, in a clockwise direction, as viewed in Fig. 5, from the operative position shown in Fig. 5 to the position shown in broken lines in this figure.

For the purpose of locking or maintaining the plate 23 in the solid line position shown in Fig. 5, spaced dogs or latching elements 34 and 35 are provided, which are pivoted, as at 36, to the lower edge 3 of the charging opening 10. These dogs or latching elements normally underlie the forward edge portion of the plate, while the rear edge of the plate rests on ledges or stops 37 extending inwardly into the cupola shaft from the rear wall of the cupola.

In order to permit the plate 23 to be rocked or oscillated to the broken line position shown in Fig. 5, I have provided means, in the form of a reciprocable rod 38, having slots 39 through which portions of the dogs 34 and 35 extend, the dogs having arcuate slots 40, through which pins 41 extend, and pins 41 extending diametrically through the rods and being riveted to the latter.

The rod 38 is adapted to be reciprocated by an air cylinder, diagrammatically represented at 42 (Fig. 4), which cylinder may, for example, be of the type known as a Bellows air motor.

In one direction of movement of the rod 38, the dogs 34 and 35 are brought into underlying relationship with the forward edge of the plate 23, while in the other direction of movement, the dogs are withdrawn from such relationship, permitting the plate 23 to be moved to the position shown in broken lines in Fig. 5.

After the openings in the plate 23 have been adjusted to predetermined size, the cupola may be charged by discharging the raw materials onto the plate while in the solid line position shown.

in Fig. 5. After each loading of the plate 23, the dogs 34 and 35 are released and the plate quickly rotated to the broken line position shown in Fig. 5, the stops 37 acting to prevent rotation of the plate through more than 180 degrees. This causes the raw materials to be dumped from the plate into the shaft, and upon completion of the dumping, the plate is quickly rotated in a counter-clockwise direction to the solid line position, ready to be again loaded.

It will be noted that in the course of rotation of the plate 23 from the solid line position shown in Fig. 5, to the broken line position, it passes through a position in which it is disposed vertically, i. e., at a position of 90° clockwise from the solid line position as viewed in Fig. 5. In the solid line position, which may be termed the "closed" position, the plate 23 at least partially obstructs charging of raw materials into the shaft, depending upon the extent to which the plates 26 have been moved over the openings 24 and 25. In the 90° position, to which I have referred, which may be termed the "open" position, the plate 23 has virtually no obstructive effect, insofar as passage of raw material into the shaft is concerned.

The flange or lip 31 prevents the raw materials, as they are dumped from the plate 23, from dropping too quickly, which might cause undesirable piling of the materials at one point or side of the cupola. In other words, it tends to cause more uniform distribution of the dumped raw materials.

After the cupola has been charged, the plate 23 is returned to its solid line position, where it is ready for its pressurizing function.

In order to avoid interference with the rotary movement of the plate 23 as well as to provide for a more economical construction, the refractory lining of the four walls of the cupola may be replaced with cast iron block or formed of welded sheets of stainless steel or Inconel for a distance extending approximately two feet above and below the charging opening. Thus a maintenance problem is substantially avoided and the possibility of refractory becoming dislodged and interfering with movement of plate 23 is also avoided.

By the use of pressurizing means or devices of the character described, I am able to use relatively high air pressures in the combustion zone of the cupola, thereby providing improved combustion, hotter iron, increased melt per square inch of cupola cross-sectional area, greater fuel economy and more uniform operation of the cupola, and to avoid or minimize bridging of the cupola by slag.

It is to be understood that the forms of my invention, herewith shown and described, are to be taken as preferred examples of the same, and that various changes in the shape, size and arrangement of parts may be resorted to without departing from the spirit of my invention, or the scope of the subjoined claims.

Having thus described my invention, I claim:

1. In combination with a cupola shaft, means for pressurizing said shaft, said means comprising at least one plate within the shaft having an opening therein of lesser area than the internal cross-sectional area of said shaft at the level at which the plate is disposed, said plate being pivoted about a fixed horizontal axis and movable from a closed position in which it partially obstructs charging of raw materials into the shaft to an open position.

2. The combination, as defined in claim 1, in which said shaft is of rectangular cross-section, and said plate is of corresponding rectangular form.

3. In combination with a cupola shaft as claimed in claim 1 in which there is provided, means for selectively pressurizing said shaft at different air pressures, said means comprising a series of plates having openings therein, the openings being graduated in area as between the different plates.

4. The combination, as defined in claim 3, in which said plates are movable from a closed position in which they partially obstruct charging of raw material into the shaft to an open position in which they have no obstructing effect.

5. The combination, as defined in claim 4, in which said shaft is of rectangular cross-section, and said plates are of corresponding rectangular form.

6. In combination with a cupola shaft of rectangular cross-section, one wall of said shaft being formed to provide a recess and means for selectively pressurizing said shaft at different air pressures, said means comprising a series of plates having openings therein, the openings being graduated in area as between the different plates, said plates being movable from an inoperative position wholly within said recess to an operative horizontal position transversely of said shaft.

7. The combination, as defined in claim 6, in which said plates are mounted for pivotal movement between operative and inoperative positions.

8. The combination, as defined in claim 1, in which means are provided for supporting one edge of said plate when in operative position, and other means are provided for withdrawing said supporting means when it is desired to move said plate to inoperative position.

9. The combination, as defined in claim 8, in which said shaft is of rectangular cross-section, and said plate is of corresponding rectangular form.

10. In combination with a cupola shaft as claimed in claim 1 in which means for pressurizing said shaft are provided, said means comprising a plate having a plurality of openings therein, and means for varying the effective area of said openings.

11. The combination, as defined in claim 10, in which said plate extends transversely of said shaft and is movable about an axis diametric of said shaft, whereby the plate may be used to dump materials charged thereonto into the shaft.
